UNITED STATES PATENT OFFICE.

WILLIAM BUNTING, JR., OF FLUSHING, ASSIGNOR TO THE MEYER-SNIFFEN COMPANY, LIMITED, OF NEW YORK, N. Y.

DESIGN FOR A LAVATORY OR SINK TRAP.

SPECIFICATION forming part of Design No. 22,785, dated September 12, 1893.

Application filed February 28, 1893. Serial No. 464,134. Term of patent 14 years.

To all whom it may concern:

Be it known that I, WILLIAM BUNTING, Jr., a citizen of the United States, and a resident of Flushing, in the county of Queens and State 5 of New York, have invented and produced a new and original Design for Lavatory and Sink Traps, of which the following is a specification.

In the accompanying drawings, Figure 1 is o a front elevation of a lavatory or sink trap showing my design; and Fig. 2 is an edge view of the same.

The design relates to traps for lavatories and sinks and consists in the shape or form 5 thereof. The trap is formed of a straight vertical portion 1, a curved or bent portion 2, and a central portion 3. The curved or bent portion 2 commences at the lower portion of the straight vertical part 1, and extends first o downwardly and outwardly, then downwardly and inwardly, then upwardly and outwardly, then upwardly and inwardly and terminates in a downward direction at 3, about centrally between the downwardly curved portion on 5 one side and the upwardly curved portion on the other side of the trap and about axially in

line with the downwardly extending straight portion 1.

What I claim, and desire to secure by Letters Patent, is—

The design for a lavatory or sink trap consisting of the straight vertical portion 1, and the curved or bent portion 2 commencing at the lower portion of the straight vertical part 1 and extending first downwardly and outwardly, then downwardly and inwardly, then upwardly and outwardly, then upwardly and inwardly and terminating in a downward direction at 3 about centrally between the downwardly curved portion on one side and the upwardly curved portion on the other side and about axially in line with the downwardly extending straight portion 1, as shown and described. 30 35 40

Signed at New York, in the county of New York and State of New York, this 20th day of February, A. D. 1893.

WILLIAM BUNTING, JR.
